(57) **CLAIM**

The ornamental design for an unzippable hat with snaps as shown and described.

DESCRIPTION

FIG. 1 is a perspective view of an unzippable hat with snaps showing the new design;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a bottom view thereof;

FIG. 8 is a front view thereof, with the hat partially unzipped, with engaged snaps; and,

FIG. 9 is a top front perspective view thereof, with the hat fully unzipped.

The broken lines represent parts of the unzippable hat with snaps that do not form any part of the claimed design. The bracket in FIG. 9 represents separation of the unzippable hat with snaps along a zipper.
